UNITED STATES PATENT OFFICE.

ICHIRO MOTONO, OF NEW YORK, N. Y.

BOOK HOLDER.

Application filed October 12, 1925. Serial No. 62,111.

This invention relates to book holders.

The principal object of the present invention is to produce a book holder which will support a book in opened condition in a manner so that a person in a comfortable reclining position may conveniently read the book.

Another object of the invention is a book holder which serves to support a book in an opened condition so that the leaves or pages of the book will face downwardly at an angle, with the pages or leaves being prevented from turning over by a means which also prevent the book from falling out of the holder body, and the said means being operable upon the movement of the holder body to permit the pages or leaves of the book to be turned over.

The nature of the invention and its distinguishing features and advantages will appear when the following specification is read in conjunction with the accompanying drawing, in which

Figure 1 is a front elevation of the book holder embodying the present invention.

Fig. 2 is a view illustrating the book holder supported in the position in which a book will be disposed in a condition in which it may be read by a person in a reclining position; the book holder being shown partly in section and partly in elevation, the section being taken substantially on the line 2—2 of Fig. 1 and looking in the direction indicated by the arrows.

Fig. 3 is a sectional view of the book holder taken substantially on the line 3—3 of Fig. 1, the book holder being shown in a position to permit the pages or leaves of the book to be turned over while in the holder body, or to permit the book to be removed therefrom.

In accordance with the present invention the book holder will be supported at the desired elevation either upon a supporting stand or upon a portion of a bed so that a person in a reclining position may conveniently read a book supported by the holder. In the drawing the book holder is shown as supported on a stand merely as an example of one manner of use of the book holder. The book holder 10 includes a holder body 11, which may be of any preferred construction and which may be made of any preferred material. In the present instance the holder body 11 consists of a top 12, bottom 13 which constitutes a rest, sides 14 which

connect the top 12 and bottom 13, and back members or slats 15 which are connected to the sides 14. Attaching means 16 is provided which tiltably supports the body holder 11. In the present instance the means 16 consists of a yoke 17 having an attaching lug 18. The yoke 17 has end members 19 which are connected respectively as at 20 to the sides 14 and thus constitute levers at the opposite sides of the holder body 11. The attaching lug 18 is attached to the member 21 which connects the end members 19, and carries means in the form of a wing nut 22, or any other suitable means may be provided for connecting the yoke to a suitable support such as the support or stand 23. It will now be understood that the holder body 11 may be tilted to be disposed in the position shown in Figs. 2 and 3. A handle 24 attached to the bottom 13 is provided for tilting the body holder 11. Means in the form of a spring 25 is attached as at 26 to the member 21 of the yoke 17, and the opposite end of the spring is held in place by a stud 27 carried by one of the slats 15. Holding members 28 and 29 are employed to extend respectively near the top and bottom of the holder body transversely with respect thereto and serve for preventing the pages of the book from turning over, and also for preventing the book from falling out of the holder body when the same is in the position shown in Fig. 2. The holding members 28 and 29 are movable to different positions simultaneously in response to the tilting movements of the holder body 11, and this is accomplished by the means presently to be described.

At each side of the holder body 11, and connected to the end member 19 thereat are arms 30 and 31, one end of each of the arms 30 and 31 being pivotally connected as at 32 to the portion of said end member or lever 19. A bell-crank lever 33 is pivotally connected as at 34 to the arm 30, and the part 35 of said lever adjustably supports the holding member 28. The holding member 28 is adjustable by virtue of a slot 36 in each of the parts 35 into which the opposite ends respectively of the holding member 28 extend. Suitable clamping nuts 37 are employed for maintaining the holding member 28 in the different adjustable positions; there being calibrations 38 on each part 35 to constitute a gauge for insuring the proper horizontal dispositions of the holding member 28. The lever 39 is employed and

2
has one end thereof pivotally connected as at 40 to the arm 31 and the opposite end thereof is pivotally connected as at 41 to an arm 42 which is pivotally connected as at 5 43 to a bell-crank lever 44. The holding member 29 is carried by the levers 44. Attached to each of the sides 14 is a casing 45, one wall of which has an opening 46 to permit the holder body 11 to have movement 10 with respect to its related end member 19, and the opposite wall of the casing has an opening 47 to permit the movement of its related lever 33, and an opening 48 to permit the movement of its related lever 44.

15 When the holder body 11 is in the position shown in Fig. 3 a book in opened condition may be arranged in the holder body 11 to be supported on the bottom 13. In the position of the holder body 11 mentioned the holding 20 members 28 and 29 will be disposed outwardly away from the holder body by virtue of the lever and arm arrangement between the holding members 28 and 29 and the end members 19. The pages of the book may be 25 readily turned over. When the holder body 11 is tilted to be disposed in the position shown in Fig. 2, the holding members 28 and 29 will be simultaneously moved toward the holder body 11 in response to this tilting movement of the latter by virtue of the lever and arm arrangement, thus the holding member 28 and 29 will prevent the pages of the book from turning over and will also prevent the book from falling out of the 30 holder body 11. The book in the holder body in the position shown in Fig. 2 will have the pages thereof disposed face downwardly at an angle so that the contents thereof may be conveniently read by a person reclining. From the foregoing it will be apparent that the holding members 28 and 29 will be moved to active and inactive positions in response to movements of the holder body 11 thus making the book conveniently 35 accessible for turning over the pages thereof and without possibility of the book falling as it is moved from one position to another for the page turning operation.

40 In order to make provision for marking 50 the place in the book at which reading was discontinued there is employed a cord 49, one end of which is attached as at 50 to the bot-

tom 13, and the opposite end of the cord is provided with a hook 51 which is releasably engageable with an eye 52 attached to the 55 top 12. The cord 49 is used when the book is closed.

It is to be understood that the invention is not restricted to the precise arrangement of parts shown and described, as details of construction may be modified and rearranged without departing from the spirit of the invention, the scope of which is limited only by the terms of the appended claims.

65 What I claim is—

1. A book holder comprising a holder body for supporting a book in opened condition, means for tiltably supporting the holder body, the holder body being movable to a position in which the pages of the book will 70 face downwardly at an angle, and said holder body being movable to a position in which the pages of the book will face upwardly at an angle, holding members pivotally mounted on the holder body for maintaining the 75 book in opened condition and for preventing the pages from turning over and for preventing the book from falling out of the holder body, the holding members being in active 80 position when the holder body is in the first mentioned position, said holding members being in inactive position when the holder body is in the second mentioned position, and means connected to the holding members operable in response to the movement of the 85 holder body for effecting the movement of the holding members to the active and inactive position.

2. A book holder comprising a holder body for supporting a book in opened condition, 90 attaching means for movably supporting the holder body, holding members for maintaining the book in opened condition and for preventing the pages from turning over and for preventing the book from falling out of the holder body, the holding members being 95 movable to permit the book to be removed from the holder body, and an arm and lever arrangement connected between said attaching means and said holding members for effecting the movement of the holding members to active and inactive positions in response to the movement of the holder body.

100 ICHIRO MOTONO.
